UNITED STATES PATENT OFFICE.

JOHN SUTLIFF, SR., OF HUNTSVILLE, MISSOURI.

MOTOR.

SPECIFICATION forming part of Letters Patent No. 257,103, dated April 25, 1882.

Application filed September 13, 1881. (No model.)

To all whom it may concern:

Be it known that I, JOHN SUTLIFF, Sr., of Huntsville, in the county of Randolph and State of Missouri, have invented a new and Improved Motor, of which the following is a specification.

The invention consists of a tubular lever pivoted on the edge of a water-tank, the inner or longer end of this lever terminating in a ball or a hollow vessel and the outer end being connected by a connecting-rod with a cog-wheel engaging with a pinion on the driven shaft. The above-mentioned connecting-rod is connected by means of an additional connecting-rod with a box containing a weighted ball, which box is arranged above and connected with a bellows connected by a flexible tube with the tubular lever, all these parts cooperating, as will be more fully described hereinafter.

Reference is to be had to the accompanying drawing, forming part of this specification, in which a longitudinal sectional elevation of my improved motor is represented.

25 A tubular lever, A, is pivoted on the upper edge of a water-tank, B, and the inner or long arm of this lever terminates in a bulb or hollow vessel, C. The shorter or outer arm, D, of this lever A is connected by means of a connecting-rod, E, with a cog-wheel, F, engaging with a pinion, G, mounted on the shaft H, which is to be driven. A connecting-rod, J, connects the connecting-rod E at a short distance from its upper end with the end of a pivoted box, K, containing a weighted ball, L, or equivalent. The under side of the box K, at the end opposite to the one to which the rod J is pivoted, is attached to a bellows, M, from which a flexible tube, N, leads to the hollow

40 shaft A.

O is a valve to supply the waste of air. The operation is as follows: If the several parts are in the position shown, the bulb or vessel C is filled with air and will rise, where- 45 by the end D of the lever will be lowered and

the wheel F and pinion G will be rotated; but at the same time that end of the box K to which the end of the rod J is pivoted will be lowered by this rod J, and the ball L will roll down the box K, and will increase the weight 50 on that end of the box to which the rod J is pivoted. The weight of this ball draws downward on the rod J, and thus also assists in operating the motor; but as one end of the box K is lowered the other end, which is attached 55 to the bellows M, must be raised, whereby all the air will be removed from the bulb C and the tube A, causing the bulb C to sink; but thereby the end D of the lever A is raised, and the wheel F, which has made a half-revolution 60 when the lever A and bulb C were raised, will now complete its revolution. At the same time that end of the box K to which the rod J is pivoted will be raised, and the ball L will roll toward the other end, which is lowered, whereby the bellows M will be compressed and air forced into the bulb C and pipe A, causing the same to rise, and so on alternately.

Having thus fully described my invention, I claim as new and desire to secure by Letters 70 Patent—

1. In a motor, the combination, with the tubular lever A, pivoted on the edge of a water-tank, of devices for automatically and alternately filling this lever and its bulb with air 75 and then exhausting the air, substantially as herein shown and described, and for the purpose set forth.

2. In a motor, the combination, with the water-tank B, of the tubular lever A, terminating 80 in a bulb, C, of the connecting-rods E and J, the wheel F, the pivoted box K, the weight L, the bellows M, and the flexible tube N, substantially as herein shown and described, and for the purpose set forth.

JOHN SUTLIFF, SR.
